UNITED STATES PATENT OFFICE.

GEORGE LIPSCHUTZ, OF PHILADELPHIA, PENNSYLVANIA.

ADJUSTABLE FIXTURE STRAP.

Application filed March 10, 1926. Serial No. 93,556.

My invention relates to those devices which are particularly adapted for use in installing electrical fixtures and relates more particularly to a fixture strap by means of which a fixture supporting stud may be secured in position.

In a great number of electrical installations, especially where it is found desirable to employ a ceiling or wall box, it is the usual practice to mount the electrical fixture upon a stud projecting from the wall or ceiling, as the case may be. That part of the fixture which is not ornamental and which serves primarily as the fixture support is covered by an ornamental plate having a centrally disposed aperture through which the fixture stud projects. The stud or nipple, which is hollow to permit passage therethrough of the electric wires, is in most cases mounted upon a strap which in turn is supported upon the edges of the wall or ceiling box. It is the usual practice to provide this strap with a fixedly located threaded aperture, usually centrally located, in which the stud is threaded supported. I have found that in a great number of instances constructional details of the walls and ceilings make it imperative that the box be located in a certain place. Due to the fact that the stud securing aperture is fixed with respect to the box it then becomes impossible to properly and with exactitude locate the electrical fixture so far as symmetry with respect to other and neighboring fixtures is concerned. Also, there are instances when the hole in which the box is to be accommodated has been incorrectly located in the wall or ceiling with the result that either the hole must be filled in and a new one made or else the fixture mounted in inexact and undesired position.

It is among the general objects of my invention to provide a fixture strap which has an adjustable aperture such that the fixture supporting stud which is received in this aperture is made independent of the location of the box within comparatively wide limits with the result that the heretofore existing defects and objectionable features are entirely eliminated. A further object is the provision of a fixture strap which is adapted to be carried by the conduit box in the usual manner but having an adjustably mounted member in which is threaded received the main feature supporting element. A still further object is the provision of a fixture

strap which permits the location of the electrical fixture irrespective of the location of the wall or ceiling box. A still further object is the provision of an adjustable wall or ceiling fixture strap which is compact, strong, and exceedingly simple and cheap to manufacture. Other objects will appear more fully hereinafter.

My invention consists substantially in the construction, combination, location and relative arrangement of parts, all as will be more fully hereinafter set forth, as shown in the accompanying drawings, and finally pointed out in the appended claims.

In the drawings:

Figure 1 is a side view of the fixture strap showing it in its relation to the fixture which it supports.

Fig. 2 is a perspective of the strap.

Fig. 3 is a bottom plan view of the strap.

Fig. 4 is a view on line 4-4 of Fig. 3.

Fig. 5 is a side view of the fixture strap showing it in its adjusted relation with respect to a wall fixture.

The same part is designated by the same reference numeral whenever it occurs throughout the several views.

Referring more specifically to the drawings the fixture strap comprises generally a main body or base member 10 on which is adjustably mounted the sliding member 11. Both members 10 and 11 are preferably formed of sheet metal stampings. The main body member 10 is provided with a centrally disposed elongated aperture or slot 12, which slot extends longitudinally throughout the major extent of the body. Provided at opposite ends of the body 10 are elongated openings 13 extending longitudinally and transversely of the body through either set of which pass retaining screws 14 for securing the strap to the box 15. The sides of the body 10 opposite the longitudinally extending aperture 12 are turned downwardly as at 16 to provide not only sliding surfaces 17 of minimum width without sacrificing the strength of the main body of the strap, but also to form locking abutments for preventing unintentional rotation of the lower securing elements for the sliding member 11.

This sliding member 11 is of substantially inverted channel formation provided with laterally extending flanges 18-18. The base 19 of the channel, which is spaced from the main body 10, is provided in its center with

a threaded aperture 20 in which is received the fixture stud 21. Bolts 22, having their shanks projecting through suitably formed apertures in the flanges 18-18 and through 5 the slot 12, are provided together with nuts 23 for adjustably mounting the member 11 upon the body 10. Rotation of these nuts 23 is prevented by the downturned sides 16 of the main body member 10. It will thus 10 be seen that the slot 12 serves as a guide for the member 11, the bolts 12 acting effectually to prevent relative turning and lateral shifting between the members 10 and 11.

15 From the foregoing description of my invention its adaptability to meet varying conditions in the installation of electrical fixtures becomes immediately apparent. In Fig. 1 my fixture strap is shown mounted 20 upon the box 15 with the adjustable member 11 in central position. In such position the fixture supporting stud 21 projects centrally into the box 15 and the exterior ornamental plate or cover 24 is disposed symmetrically to cover the box. In Figure 5, however, the conditions have been altered. In this case it was found necessary to locate the box 15 such that it is not axially coincident with the fixture supporting stud 21. To 25 meet such a contingency the member 11 has been shifted with respect to its supporting body 10 such that the threaded aperture 20 is axially coincident with the desired location of the stud axis. The fixture 25 may 30 thus be mounted in its proper position irrespective of the location of the box 15. The exterior cover 24, while eccentrically located with respect to the axis of the box 15, still covers the box exactly as in the arrangement 35 shown in Fig. 1.

Having now set forth the objects and nature of my invention and a construction embodying the principles thereof, what I claim as new and useful and desire to secure by 45 Letters Patent is:—

1. A fixture supporting strap comprising a main body member provided with an opening extending longitudinally thereof, and a member carried by said body member and 50 arranged for sliding movement thereon, the central portion of the body of said sliding member lying in a plane spaced from and paralleling said main body member and provided with a threaded aperture for reception 55 of a fixture supporting nipple.

2. An adjustable wall or ceiling bracket comprising a main body member having an elongated slot extending longitudinally thereof, a member of substantially channel 60 shape in longitudinal section, said channel member being provided with oppositely projecting tabs overlying said slot, and means carried by said tabs and projecting through

said slot whereby to permit longitudinal adjustment of said channel member on the 65 main body member.

3. An adjustable wall or ceiling bracket comprising a plate of a length sufficient to span the walls of a junction box, said plate being apertured at the ends thereof for reception of screws for attaching said plate to said box, a member mounted upon the upper surface of said plate, the main body portion of said member being relatively offset from said plate and being provided with a 70 threaded aperture for the reception of a fixture supporting nipple, and means for affording longitudinal adjustment of said member on said plate whereby said fixture may be positioned at any point within the 75 range of movement of said longitudinally adjustable member.

4. An adjustable fixture strap comprising a main body member provided with an elongated slot extending longitudinally throughout the major extent thereof, a member of substantially inverted channel section carried by said main body member, the base of said channel member being provided with a 80 threaded aperture for the reception of a fixture supporting nipple, flanges projecting oppositely from the walls of said channel, each of said flanges having an aperture in registry with said elongated slot, and means projecting through said registering 85 apertures and slot adapted to maintain said members in slidably disposed relation.

5. In a fixture support, a plate having ends and side edges, said plate having transversely disposed apertures in the opposite ends thereof and an elongated longitudinal slot intermediate said apertures, a support bracket, a bolt transversing said slot for clamping said bracket to said plate in any of a plurality of positions longitudinally of 100 the plate, and means on the side edges of said plate for guiding and retaining engagement with the nut of said bolt.

6. In a fixture support, a plate, said plate being provided at opposite ends thereof with means permitting attachment of said plate to an outlet box, said plate having a slot formed longitudinally therein, a support bracket adapted for sliding engagement over one face of said plate, a clamping bolt extended through said support bracket and plate slot for clamping said bracket in any of a plurality of positions longitudinally of the plate, a nut on said bolt for effecting 110 clamping engagement thereof, and bevelled side edge portions on said plate, said portions extending into guiding and locking engagement with said nut.

In testimony whereof I hereunto affix my signature.

GEORGE LIPSCHUTZ.
